(57) **CLAIM**

The ornamental design for a dispenser, as shown and described.

DESCRIPTION

FIG. 1 is an isometric view looking from the left front of the dispenser in a closed position in accordance with the invention.

FIG. 2 is a side elevation of the dispenser looking from left to right with respect to the isometric view illustrated in FIG. 1 of the dispenser in FIG. 1. The right side view is a mirror image of the left side view shown in FIG. 2.

FIG. 3 is a front elevation of the dispenser in accordance with my invention in a closed position.

FIG. 4 is a top view of the dispenser of my invention as illustrated in FIGS. 1, 2 and 3.

FIG. 5 is a rear elevation view of the dispenser in accordance with my invention as illustrated in FIGS. 1-4; and, FIG. 6 is an isometric view of the dispenser in accordance with my invention taken at the same position as in FIG. 1 but showing my dispenser in an open position.

The bottom view of my dispenser looks essentially the same as the rear view illustrated in FIG. 5.
